UNITED STATES PATENT OFFICE.

ALEXANDER WADDELL, OF DUNFERMLINE, SCOTLAND.

PROCESS AND APPARATUS FOR THE TREATMENT OF COAL, SHALE, OR THE LIKE IN VERTICAL RETORTS.

1,103,112.

Specification of Letters Patent.

Patented July 14, 1914.

Application filed September 11, 1913. Serial No. 789,306.

To all whom it may concern:

Be it known that I, ALEXANDER WADDELL, a subject of the King of the United Kingdom of Great Britain and Ireland, and residing at Dunfermline, Scotland, have invented a certain new and useful Process and Apparatus for the Treatment of Coal, Shale, or the like in Vertical Retorts, of which the following is a specification.

10 In the carbonization of coal, shale, or the like in vertical or substantially vertical retorts, the heat applied to the outside of the retort takes a comparatively long time to carbonize the whole of the mass within the retort, the time varying according to the thickness of the mass.

15 The invention provides for reduction of the distance necessary for the heat to travel toward the less carbonized part of the mass by causing that part of the mass to come nearer to the hot retort walls, and also utilizes the comparatively highly heated portion to assist in carbonizing the less heated material by causing these to commingle. To 20 this end means are provided affording a temporary support (at a suitable position or positions) for a section or sections of the usual uncarbonized or partly carbonized center or core of material, said means being 25 insertable and withdrawable, while the retort is in use, being inserted to support or envelop the center or core, while a carbonized portion of the mass at the bottom of the retort is withdrawn.

30 A retort equipped with the present improvements is illustrated in the accompanying drawings in which Figures 1 and 2 are respectively a vertical and a horizontal section of parts of a retort rectangular in plan, and showing the supporting device in its operative position; Figs. 3 and 4 are transverse vertical sections to a reduced scale showing diagrammatically how the material within the retort descends when the supporting device is in position and a carbonized portion of the mass at the bottom of the retort is withdrawn.

35 As shown, the retort A is rectangular in

plan. An aperture A¹ is formed in the retort wall at any desired level to permit of the insertion into the retort of a core-supporting device B. This device is of metal and is of open-ended box form, its upper surface being of inverted V-form and the lower edges of each side being turned inward to form flanges to which is secured a rack B¹ forming the bottom of the box. When inserted it extends across the retort in the direction of its greater horizontal dimension, and it is of less width than the retort, so that there are spaces between its sides and the walls of the retort. The device is supported by rollers B², one on each of its sides running on rails C carried at their ends by metal liners C¹, C² extending around parts of the aperture A¹ in the retort wall, and also by a flanged roller D bearing on its upper surface, and a pinion D¹ gearing with the rack B¹. The pinion is on a shaft which may be rotated by either hand or power, and when the pinion is rotated, the core supporting device B is either inserted or withdrawn, depending on the direction of rotation of the shaft. The forward edge of the device B is serrated to facilitate its cutting its way through the mass of material within the retort.

40 What takes place in the process of carbonization, according to this invention, is shown diagrammatically in Figs. 3 and 4, the carbonized or highly heated portion of the mass being shown by single hatched lines E, while the core or less carbonized part of the mass is represented by cross hatched lines E¹.

45 When a carbonized portion of the mass at the bottom of the retort is to be withdrawn, the device B is first inserted, as hereinbefore described, and being of open-ended box form, on entering the retort, it takes within it and holds up a section of the uncarbonized or partly carbonized center or core of material, this section being shown at G in Figs. 3 and 4.

50 The core-supporting device B being in position within the retort when a with-

drawal takes place the material within the retort up to the level of the top of the device first falls a distance equivalent to the amount drawn off at the bottom, the material between the support B and retort walls falling beneath the support and momentarily leaving a space as shown in Fig. 3. This space is, however, at once filled by the descent of the material above the support, as shown in Fig. 4, the comparatively hot and the cooler portions commingling when so falling. Part of the less carbonized central core E¹ of the mass is thus not only brought nearer to the hot retort walls, but as it is also commingled with the comparatively highly heated portion and part of that portion is thrown nearer the center of the mass in its descent, the carbonization of the whole mass is thereby facilitated.

Upon the withdrawal of the supporting device, the section G of the core falls slightly, and upon the reinsertion of the supporting device a part of this section with a fresh part of the uncarbonized material E¹ above it is again taken into the device.

To insure that, when the supporting device is to be withdrawn, it does not take with it the core G of material which is then within it, a plate G¹ of an external contour to fit loosely within the supporting device B is inserted within the device until it abuts the outer end of the core G. The plate G¹ is carried by rods H which extend out to a distance beyond the outer end of the supporting device B at least as great as that of the length of the part of that device which projects into the retorts. During the first part of the withdrawal of the supporting device B the rods H, and consequently the plate G¹, are held stationary; and as the plate G¹ is then bearing on the core G, the latter is prevented from movement and left in the retort. When the inner end of the device B has traveled out to the plate G¹, both are then further withdrawn together until they leave the aperture A¹ which is then closed by a door (not shown). The aperture A¹ is fitted with a gas offtake which may be fitted with means for closing it when the door is open.

One or a plurality of apertures and supporting devices at different levels may be used.

Having now described my invention what I claim and desire to secure by Letters Patent of the United States is:—

1. The herein-described improvement in the art of retorting coal, shale and the like, consisting in enveloping and supporting a section of the central portion of the materials in the retort and simultaneously withdrawing a portion of the material at the bottom of the retort, so as to cause the section of the central portion located above the enveloped section to approach nearer to the

walls of the retort and to commingle with the exterior portion, without substantial displacement of the enveloped section.

2. The herein-described improvement in the art of retorting coal, shale and the like, 70 consisting in enveloping and supporting a section of the central portion of the materials being retorted and simultaneously withdrawing a portion of the material below the supported section, so as to cause the material above the enveloped section to fall and fill up the space surrounding the enveloped section and to cause the section of the central portion above the enveloped section to approach nearer to the walls of the 80 retort and to commingle with the exterior portion, without substantial displacement of the enveloped section.

3. The herein-described improvement in the art of retorting coal, shale and the like, 85 consisting in enveloping and supporting a section of the central portion of the materials in the retort, the enveloped section having vertical sides spaced a short distance from, and substantially parallel with, 90 the side walls of the retort, and withdrawing a portion of the materials at the bottom of the retort while said section continues to be enveloped and supported so as to cause the section of the central portion located above 95 the enveloped section to approach nearer to the walls of the retort and to commingle with the exterior portion, the commingled product filling the space between the vertical sides of the enveloped section and the 100 side walls of the retort.

4. The combination with a vertical retort having an apertured wall of a core-sustaining device movable through the aperture transversely of the retort, said device being 105 of open-ended box form and adapted when inserted into the retort to envelop a section of the core, and so dimensioned as to leave spaces between its sides and the walls of the retort.

5. The combination with a vertical retort having an apertured wall, of a core-sustaining and enveloping device movable through the aperture transversely of the retort, and of less cross sectional area than the retort, 115 said device being provided with rack teeth, and a pinion engaging said rack teeth and adapted when rotated to reciprocate said device.

6. The combination with a vertical retort having an apertured wall, of a core-sustaining device movable through the aperture transversely of said retort, said device being of open-ended box form and adapted when inserted into the retort to envelop a section 120 of the core and so dimensioned as to leave spaces between its sides and the walls of the retort, and a stop fitted within said core supporting device.

7. The combination with a vertical retort 130

having an apertured wall of a device movable through the aperture transversely of the retort, said device adapted to envelop and sustain a section of the central portion only of the materials within the retort and to deflect outward materials lying above the same.

5 In testimony whereof I have signed my

name to this specification in the presence of two subscribing witnesses.

ALEXANDER WADDELL.
